UNITED STATES PATENT OFFICE.

WILLIAM BLIESNER, OF ST. LOUIS, MISSOURI.

VAPOR-BURNER STOVE.

SPECIFICATION forming part of Letters Patent No. 327,647, dated October 6, 1885,

Application filed February 14, 1885. Serial No. 155,952. (No model.)

To all whom it may concern:

Be it known that I, WILLIAM BLIESNER, of St. Louis, Missouri, have made a new and useful Improvement in Vapor-Burner Stoves, of 5 which the following is a full, clear, and exact description.

The improvement relates to the mechanism for operating the burner-valve.

The annexed drawings, making part of this 10 specification, illustrate that portion of a vapor-burner stove with which the improvement in question is immediately connected and essential to an understanding thereof.

Figure 1 is a view in perspective of a burner 15 having the improvement. Fig. 2 is a horizontal section taken through the valve-stem and supply-pipe above the level of the valve-stem lever, and Fig. 3 is a top view showing a portion of the stove.

20 The same letters of reference denote the same parts.

A represents the stove. Saving as modified by the improved feature it is of the customary form.

25 B represents the burner.

C represents the stem of the burner-valve.

D represents a lever attached to the valve-stem. The lever extends from the stem outward to or into the vicinity of the front a of 30 the stove, substantially as shown in Fig. 3. The valve stem is operated by swinging the outer end of the lever horizontally to the right and left—that is, to close the burner-valve the lever is swung in one direction, say to the right, and to open the burner-valve the lever is swung in the opposite direction. The valve-stem is adapted to move, and to close or open the burner-valve according to the extent of the movement of the lever. To this end the 35 valve-stem is threaded at c, and the threaded portion is adapted to work through a bearing, c', so that as the lever is swung to and fro, as

described, the valve stem is raised and lowered in its bearing, and the person using the stove can thus both readily operate the burner, and 45 also, from the position of the lever, determine whether the burner-valve is open or closed.

The lever is adapted to operate against a stop, so that it can be readily determined when the valve is closed or opened. For this 50 purpose the lever is extended at d and d', and in each extension is an adjustable projection—say, in the form of the screw d². When the lever is swung to the right, the point of the screw in the extension d encounters some fixed 55 part of the stove—say, the supply-pipe E—and when the lever is swung to the left the point of the screw in the extension d' encounters the supply-pipe.

As the burner-valve is worn in use, or its 60 seat enlarged, it is desirable from time to time to swing the lever somewhat farther in closing the valve. For this purpose the projection d² is made adjustable, as stated, in the extension. By unscrewing the screw in the extension the lever can be moved through a greater arc, and the burner-valve accordingly 65 moved. The screw in the other extension, d', can be similarly adjusted to limit the throw of the lever in the opposite direction. 70

I claim—

1. The combination of the valve-stem C, the stop E, the lever D, the extension d, and the adjustable projection d², substantially as described.

2. The combination of the valve-stem C, the stop E, and the lever D, having the extensions d d', and the screws d² d², substantially as described.

WILLIAM BLIESNER.
